MILES SWEET, OF TROY, NEW YORK.

Letters Patent No. 89,182, dated April 20, 1869.

IMPROVED CURRY-COMB.

The Schedule referred to in these Letters Patent and making part of the same.

To all whom it may concern:

Be it known that I, MILES SWEET, of Troy, in the county of Rensselaer, and State of New York, have invented certain new and useful Improvements in construction of Curry-Combs; and I do hereby declare that the following is a full and exact description of the same, reference being had to the annexed drawings, and the letters of reference marked thereon, making a part of this specification, and showing my improvements in curry-combs, of which—

Figure 1 is a perspective view of the face side.

Figure 2 is a perspective view of the back side.

Figure 3 is a perspective view of an end-bar separate from a comb.

Figure 4 is a sectional view, showing the manner of closing the lug-blanks of the end-bars around the shank-frame.

The same letters refer to like parts in each of the said figures.

The said invention and improvements consist in my peculiar manner or method of attaching or securing a series or set of comb-bars to the shank-frame of curry-combs, by transverse connecting end-bars, or by end-pieces, formed of malleable metal, and provided with lug-blanks, in such a manner that after a set or series of comb-bars have had their respective-ends secured or riveted to the said connecting end-bars, or pieces, the said lug-blanks thereof are then closed tightly on and around the shank-frame of the curry-comb, thereby securing said comb-bars firmly to said shank-frame, in manner substantially as hereinafter fully described.

My said invention also consists in forming of and with the end, or ends of the shank-frame of curry-combs, a fender-knob, or guard, in manner substantially as and for the purpose as hereinafter fully set forth.

To enable others skilled in the art to make my invention and improvements, I now proceed to fully describe the same, to wit:

I make end-bars, or end-pieces A of malleable cast metal, which are provided with rivet-studs, or blank's a, and lug-blanks b b, in manner substantially as shown in fig. 3 of annexed drawings.

To a set, or pair of these end-bars, or pieces A, there is riveted at their respective end-parts, by rivets a, a set or series of trough-shaped comb-bars, B.

The comb-part as thus prepared, is now to be se-

cured to a frame, and its shank and handle, which I secure thereto, by first bending outwardly at about right angles with the comb ends, the ends of the shank-frame rods C, thereby forming a head, D, which serves to hold the comb from slipping off the shank-frame C.

The shank-frame sides, or rods c c, are now placed in the groove between the lug-blanks b b, which are then bent down, or closed tightly over and on the shank-side frame-rod c c, with a hammer, or by other convenient means, substantially in manner as shown in section in fig. 4 of annexed drawings, thereby securing the comb-bars B firmly and permanently to the shank-frame of the comb, and producing thereby a strong, durable comb at a moderate cost.

The ends of the shank-frame rods c c are so far bent outwards, as to project sufficiently, at about right angles to the comb-ends, that the part so bent, in addition to its holding the comb from slipping off the shank-frame end, shall also form a guard, or fender-knob, D, substantially in manner as shown in figs. 1 and 2 of annexed drawings, which knob, or fender-guard is to prevent bruising the comb-ends by rapping the said guard D, instead of the comb-ends upon any hard substance, to clean the comb of hair, or dirt, by rapping the same, as is commonly done.

What I claim as my invention, and desire to secure by Letters Patent, is—

1. A malleable cast-metal end-piece for curry-combs, having lugs b b formed thereon, and rivet-holes, or rivet-blanks a a a, cast or formed thereon, so that said piece shall not only facilitate the putting together of the parts, but serve as the means of holding them together when clinched or hammered down, as described.

2. Also in a curry-comb, a series of sheet-metal comb-bars, B, riveted to malleable cast-metal end-pieces A A, which end-pieces have lugs b b, &c., bent tight upon or around the wire frame, which is a continuation of the shank for the handle, as and for the purpose set forth.

3. Also terminating the outer ends of the wire frame in knocking-lugs, or fenders D D, as and for the purpose set forth.

MILES SWEET.
